Edward J. Bair, New Hartford, N. Y., assignor to
Utica Radiator Corporation, Utica, N. Y., a cor-
poration of New York

Application October 10, 1933, Serial No. 49,441

Term of patent 14 years

To all whom it may concern:

Be it known that I, EDWARD J. BAIR, a citizen
of the United States and a resident of New Hart-
ford, Oneida County, State of New York, have in-
vented a new, original, and ornamental Design
for a Combined Radiator Section and Humidi-
fying Well of which the following is a specifica-
tion, reference being had to the accompanying
drawing, forming part thereof, wherein

Fig. 1 is a side elevation,
Fig. 2 is a front elevation, and
Fig. 3 a top view of a radiator section embody-
ing my invention.

Fig. 4 is a perspective view thereof.

I claim:

The ornamental design for a combined radiator
section and humidifying well, as shown.

EDWARD J. BAIR.
